JOSEPH TRENT, OF MILLERTON, NEW YORK.

Letters Patent No. 76,557, dated April 7, 1868.

IMPROVEMENT IN VOLUTE SPRINGS.

The Schedule referred to in these Letters Patent and making part of the same.

TO ALL WHOM IT MAY CONCERN:

Be it known that I, JOSEPH TRENT, of Millerton, in the county of Dutchess, and State of New York, have invented a new and useful Improvement in Volute Springs; and I do hereby declare that the following is a full, clear, and exact description of the same, reference being had to the accompanying drawings, forming part of this specification, in which—

Figure 1 is a side elevation of the complete spring.

Figure 2 is a longitudinal vertical section thereof, taken on the plane of the line $z z$, fig. 1.

Figure 3 is a plan view of a strip of metal before the same is rolled up to constitute the spring shown in fig. 1.

This invention consists in a new article of manufacture, namely, a quadruple volute spring, formed by rolling up a plate or strip of metal having four legs or arms, two at each end, the said arms being separated by somewhat V-shaped slots; thereby producing a quadruple volute spring, possessing great sustaining power, with a requisite amount of flexibility.

It also consists in an improved mode or manner of constructing the said plate of which the spring is formed, to wit, by punching out or otherwise removing from said plate a somewhat V-shaped piece or pieces, the practice heretofore having been to cut a slit in the metal, and forcing apart the separated pieces to form the legs or arms, as described in a patent granted to one Freeland and one Ward on the 7th March, 1865; one of the great disadvantages to this last-named practice being that the legs or arms are liable to get back to their normal condition or "set," thus destroying the effective qualities of the spring, whereas, with my invention, the legs or arms are naturally at a certain distance apart, and when pressed together, as when the spring is sustaining a weight, they immediately resume their normal condition when the pressure is relieved, thereby obviating any material "set" in the spring.

In the manufacture of the spring, a number of plates may be struck in the required shape by a stamping machine.

In fig. 1 of the drawings I have shown a plate of a construction which I find it preferable to use. A designates the solid central portion of the plate or strip, and B B the legs or arms on the one side, and B' B' the legs or arms on the other side. In forming these legs, a somewhat V-shaped piece is stamped out or otherwise removed from each end of the plate or strip, whereby great advantage is obtained, as above mentioned.

At the apex of each slot I find it preferable to make a puncture or hole, a , which has the effect, when the plate or strip is rolled up to form the spring, to prevent the two arms of each set crowding past or overlapping each other—a contingency likely to occur were the slot to terminate at a sharp angle. The advantages arising from forming a puncture or hole at the termination of each slot will be easily perceived by compressing the spring to its minimum capacity.

I also find it preferable to form the arms B B and B' B' with parallel outer edges, b , commencing at their ends, and extending up a sufficient distance to insure, when the plate or strip is rolled up to form the spring, an even base at both ends for the spring to rest upon; and at the termination of the parallel edges the outer edges of the plate are curved concavely, the greatest depth of the curve being at about the centre of the solid portion A. This curving of the plate gives the spring, it is believed, greater elasticity or flexibility.

The plate or strip, whether it be simply a plate or strip having a V-shaped piece cut out from each end, or whether, in addition to this, having the punctures b , parallel bases, and curved edges, may be rolled up around a mandrel, or in any other suitable manner; and when so made it possesses many advantages over any spring of the same character now known. It is in effect equal to four ordinary volute springs combined in one and operating jointly, thus giving the spring great strength, and yet sufficient elasticity. Pressure upon it, while producing a vertical motion, tends also to move the outer coils laterally in one direction, and the inner coils in just an opposite direction, so that no liability of the spring unwinding or uncoiling need be apprehended. The compression of the spring increases its resistance; that is to say, a little weight will operate the spring at first, but afterwards, the heavier the weight, the greater the resistance, until the power of the spring is exhausted. The spring has also a lateral motion in all directions.

I am aware that a patent was issued to John Freeland and Daniel Ward, on the 7th of March, 1865, for an improvement in volute springs, wherein it was specified that a plate of metal, cut or divided longitudinally

early its whole length, with the cut portion spread apart, was rolled up to form the spring; I therefore wish distinctly understood that I disclaim everything which is shown, described, and claimed in the said patent as the invention of said Freeland and Ward; but

What I claim as my invention, and desire to secure by Letters Patent, is—

1. As a new article of manufacture, the quadruple volute spring, constructed in the manner herein set forth.
2. The improved method herein described of manufacturing double or quadruple volute springs.

JOSEPH TRENT.
